DESIGN FOR A LADY'S SHOE OR SIMILAR ARTICLE

Richard Jerro, Brooklyn, N. Y.

Application December 15, 1939, Serial No. 88,919

Term of patent 3½ years

To all whom it may concern:

Be it known that I, Richard Jerro, a citizen of Syria, residing in the Borough of Brooklyn, city of New York, county of Kings, and State of New York, have invented a new, original, and ornamental Design for a Lady's Shoe or Similar Article, of which the following is a specification, reference being had to the accompanying drawing, forming part thereof.

I claim:

The ornamental design for a lady's shoe or similar article, as shown.

RICHARD JERRO.
